UNITED STATES PATENT OFFICE.

THOMAS M. NORTH, OF NEW YORK, N. Y., ASSIGNOR TO ROBERT HOE, THEODORE H. MEAD, AND CHARLES W. CARPENTER, OF SAME PLACE.

PRINTING-PRESS.

SPECIFICATION forming part of Letters Patent No. 629,911, dated August 1, 1899.

Application filed November 22, 1897. Serial No. 659,507. (No model.)

To all whom it may concern:

Be it known that I, THOMAS M. NORTH, a subject of the Queen of Great Britain, residing at New York, (Brooklyn,) county of Kings, and 5 State of New York, have invented certain new and useful Improvements in Printing-Presses, fully described and represented in the following specification and the accompanying drawings, forming a part of the same.

10 While the present invention is applicable to various constructions of printing-presses, it is shown herein as applied to that form of rotary-cylinder press in which the impression-cylinder is of less diameter than the plate-cylinder and makes but one revolution and 15 also comes to a stop during each revolution of the plate-cylinder.

The invention includes mechanism for tripping the impression-cylinder—that is, for 20 causing it to remain at rest while the rotation of the plate-cylinder continues. The utility of this mechanism is that when the operator fails in the feeding of a sheet, or to permit mixing of the ink on the ink-plates, or if for 25 any other reason he desires to hold the impression-cylinder stationary, he can do so instantly and without stopping the other parts of the press.

The invention also includes mechanism for 30 locking the impression-cylinder when thus brought to a stop and a safety device for preventing the attempted operation of the tripping mechanism while the impression-cylinder is in motion.

35 The invention consists in certain parts, improvements, and combinations, as will be hereinafter described, and fully pointed out in the claims hereunto appended.

In the drawings hereto annexed and forming a part of this specification, Figure 1 is a side elevation of a press embodying my invention. Fig. 2 is a plan view of the same, showing the impression-cylinder partly in section. Fig. 3 is a view, on an enlarged scale, 45 of one end of the impression and plate cylinders. Fig. 4 is a view, on the same scale, of the other end of the impression-cylinder and a part of the plate-cylinder. Fig. 5 is a plan view, on the same scale, of the parts shown in Fig. 4, the line of sight being in the direction 50 of the arrow of Fig. 4. Fig. 6 is a view, on

the scale of Fig. 1, of the end of the plate-cylinder, illustrating the operation of the devices for controlling the position of the inking-rollers, a group of inking-rollers being shown as 55 raised above the surface of the plates on the cylinder and a group of rollers being shown as in contact with the same. Fig. 7 is also a view, on the same scale, of the end of the plate-cylinder and shows the press in a state of rest, 60 in which both groups of inking-rollers are lifted above the surface of the cylinder-plates. Fig. 8 is an end view of the press shown in Fig. 7, the line of sight being that indicated by the arrow in Fig. 7. 65

Referring to the drawings, A is the frame of a press embodying my invention, B a plate or form cylinder, and C an impression-cylinder. The cylinders are provided with the segmental gears D E and the coupling-levers 70 F F' for transmitting intermittent and graduated motion from the cylinder B to the cylinder C and causing the latter cylinder to come to a stop during each revolution of the former cylinder, this mechanism being the same and 75 operating in the same manner as described in my application, Serial No. 618,024, filed January 5, 1897. The cam-actuated brake G and stop H for arresting the motion of the impression-cylinder and locking it in a position of rest are also provided, as described 80 in said application. It should, however, be understood that I may employ other means than that above described for rotating the impression-cylinder. I do not limit myself 85 to the rotation of the impression-cylinder through connections with the plate-cylinder.

In order that the rotation of the impression-cylinder may be tripped when desired, the segment E is formed on a wheel or short cylinder I, detached from the cylinder C and rotating freely on the cylinder-shaft J. The wheel I has a flange i projecting within the cylinder and provided with a notch i''. A shaft K is journaled in the two ends of the 95 cylinder and carries keyed upon it an arm k, provided with a lug k'', adapted to fit the notch i''. At the other end of the shaft K and beyond the end of the cylinder is a bell-crank lever L, on one arm of which is a stud 100 l and to the other arm of which is connected a spring l', which exerts a pressure upon the

shaft K to force the lug k'' into the notch i'' . Projecting from the end of the cylinder is another stud l'' . Keyed upon the short shaft M, journaled in the frame, is the hand (or 5 foot) tripping-lever m. The shaft M is in line with the shaft K when the cylinder is stationary and carries on its end inside the frame a three-armed lever N. One arm n of this lever carries two lugs which are adapted 10 to engage with the stud l'' , as shown in Fig. 4. The second arm n' carries two lugs adapted to engage with the stud l , as shown in the same figure. The third arm n'' has pivoted thereto a link O, the other end of which is 15 slotted and rides over a pin o, projecting inward from the press-frame opposite the plate-cylinder. This link carries a lozenge-shaped stop o', which is adapted to engage with a segmental rib o'', projecting from the end of the 20 plate-cylinder. The operation of this mechanism is as follows: In normal operation the impression-cylinder is locked to the wheel I by the lug k'' entering the notch i'' , and the two move together in all respects as though 25 a solid cylinder. When it is desired to trip the cylinder, the lever m is elevated, whereupon the lug k'' is withdrawn from the notch i'' , the shaft K being rocked by the engagement of the lugs on arm n' with the stud l . 30 At the same time the lugs on arm n engage with stud l'' , and the cylinder is thereby held fast in the position it then occupies. The wheel I now revolves alone in connection with the plate-cylinder, leaving the impression-cylinder at rest. When it is desired to prevent the revolution of the cylinder for some 35 time, a pin may be inserted under the tripping-lever, as shown in Fig. 4. Where the cylinder is merely tripped because of the failure to feed a sheet and it is desired to lose but one revolution, the tripping-lever is released at once after being thrown, as described, and the spring l' forces the lug k'' into the notch i'' when this notch next comes 40 opposite the lug, thereby again locking the cylinder to the wheel I.

It is necessary to prevent attempting to trip when the impression-cylinder is in motion, as by so doing the mechanism would be 45 subjected to probable injury, and to this end the safety device, consisting of the link O and connected parts, is provided. The segmental rib o'' is of such length and position as to lie in front of the lozenge o' when the impression-cylinder is in motion and prevent movement 50 of the tripping-lever, as shown in Fig. 3. When the impression-cylinder has come to rest, the rib o'' is out of the way and the link O is free to move to the position shown in 55 Fig. 4.

It will be observed that the wheel I, owing to the extension P, on which are placed the studs or rollers p p', with which the coupling-levers engage, may not have sufficient weight 60 to of itself accurately preserve its position when disconnected from the impression-cylinder, its brake and stop, and from the plate-

cylinder. To cause it to hold its position when disconnected, the outer surface of the extension P is made concave in about the curvature of the plate-cylinder, and the latter is provided with a segmental abutment P', which is of such a length and so placed as to be opposite to and in contact with the extension P during that part of the revolution of the 70 plate-cylinder during which the cylinder is disconnected from the wheel I. The curvature of this abutment is the same as that of the extension P, and it prevents displacement 75 of the wheel I during this time. 80

The mechanism for manipulating the ink-rollers will next be described. When the ink is first put in the fountain, it is necessary to make several revolutions of the press in order to get sufficient ink on the ink plate and 85 rollers, and during this time the rollers must not come in contact with the forms. To provide for this necessity, the ink-rollers are mounted upon brackets R R', sliding in the frame of the press, and each provided with a 90 stud r. On each end of the cylinder-shaft is mounted a cam S, having a raised portion. On each end of the shaft, between the cam S and the end of the cylinder, is pivoted a lever s, which carries pivoted levers s' s'', 95 having rollers which run upon the cams S. In the position of levers s shown in Fig. 6 these levers s' s'' are in radial line with the studs r, and when their rollers ride on the raised portion of cams S they push the ink-roller brackets outward, so that the plate may 100 pass under them without contact. The raised portions of cams S correspond in length, of course, with the portion of the circumference of the cylinder occupied by the forms. 105

When the press is to be used for printing, the levers s are carried to the position shown in Fig. 1, the studs r being in that position out of the range of movement of levers s' s''. 110

When the press is stopped, it is desirable 110 to lift the ink-rollers clear of the plates, and to do this the levers s are provided with raised inclines s''', which make contact with studs r when the levers s move to the position shown in Fig. 7 and push up the brackets R R'. The 115 levers s may be operated by two segments, one on either side of the machine, connected by a shaft, as shown.

My invention includes an improvement relating to the ink-rollers, as follows: The 120 ductor-roll Y oscillates between the fountain-roll U and the distributing-cylinder V in the usual manner, it being journaled in arms fixed to the rock-shaft u. From the cylinder V roller V' conducts the ink to a group of ink-rolls on the side next to the impression-cylinder, and roller V'' conducts the ink to a group 125 on the opposite side. Now it is plain that if the roller V' runs constantly in contact with cylinder V and its group of form-rollers the 130 larger part of the ink will be carried by roller V' to the group of ink-rollers nearest the impression-cylinder. This is detrimental to good printing, since the ink does not have

sufficient distribution. It would be better if the larger part of the ink could be sent to the other group of ink-rollers, when it would be better distributed before printing. To accomplish this, I mount the roller V' on brackets swinging on the shaft of distributing-cylinder V. On each bracket is formed a toothed segment which gears with segments placed on each end of the shaft u. Therefore when the 5 shaft u rocks to throw the roller U into contact with cylinder V it lifts roller V' out of contact with its group of ink-rollers. The first and larger part of the ink thus passes onto the roller V'' and the other group of ink-rollers and is more thoroughly distributed before reaching the plates than it otherwise would be. At the same time the roller V' is 15 kept in contact with cylinder V and its full distributing-power preserved. Of course any 20 other suitable form of mechanism may be used for causing the vibration of roller V' without departing from my invention.

When the machine is used to print from planographic surfaces, a suitable damping 25 mechanism will of course be employed. Such a damping mechanism is indicated at W in Fig. 1.

What I claim is—

1. In a printing-machine, the combination 30 with a printing-couple, of a member intermittently rotated in unison with one member of the couple, connections between said member and the other member of the couple, and means for interrupting said connections at will, substantially as described.

2. In a printing-machine, the combination 35 with a rotating printing-couple, of a member intermittently rotated in unison with one member of the couple, connections between 40 said member and the other member of the couple, and means for interrupting said connections at will, substantially as described.

3. In a printing-machine, the combination 45 with a rotating form-carrying cylinder, of a rotating impression-cylinder, a member intermittently rotating in unison with the form-cylinder, connections between said member and the impression-cylinder, and means 50 whereby said connections may be interrupted at will, substantially as described.

4. In a printing-machine, the combination 55 with a printing-couple, of a member, means intermediate the said member and one member of the couple, whereby a variable rotating movement is imparted to said member, connections between said member and the other member of the couple, and means for interrupting said connections at will, substantially as described.

60 5. The combination with a pair of rotating members, of two pairs of engaging devices intermediate the members, one of the engaging surfaces of each pair being inclined to its path of movement, a third member, connections 65 between it and one of the other members, and means interrupting said connections at will, substantially as described.

6. The combination with a pair of rotating members, of two pairs of engaging surfaces having paths of movement corresponding to 70 the paths of movement of the members, means for giving one of the surfaces of each pair a movement independent of its rotating movement, a third member, connections between it and one of the pair of members, and means 75 for interrupting said connections at will, substantially as described.

7. The combination with a printing-couple, of a gear, means whereby said gear has a variable movement imparted to it by one of the 80 members of the couple, connections between said gear and the other member of the couple, and means for interrupting said connections at will, substantially as described.

8. The combination with a printing-couple, 85 of a gear, means whereby the gear has its movement gradually increased until it runs in unison with one member of the couple and then gradually decreased until it is brought to a stop, connections between said gear and 90 the other member of the couple, and means whereby said connections may be interrupted at will, substantially as described.

9. The combination with a rotating printing-couple, of a gear, means whereby the gear 95 has its movement gradually increased until it runs in unison with one member of the couple and then gradually decreased until it is brought to a stop, connections between said gear and 100 the other member of the couple, and means whereby said connections may be interrupted at will, substantially as described.

10. The combination with a constantly-rotating form-carrying cylinder, of a gear, means 105 intermediate the form-cylinder and the gear whereby the gear has its movement constantly increased from a position of rest until it runs in unison with the form-cylinder and then gradually decreased until it is brought to a stop, an impression-cylinder, connections between 110 the impression-cylinder and the gear, and means whereby said connections may be interrupted at will, substantially as described.

11. The combination with a rotating member, of a second rotating member, means for 115 connecting and disconnecting the two members, means for maintaining the second member in a position of rest when it is disconnected from the first member, a third member, connections between it and the second 120 member, and means for interrupting said connections at will, substantially as described.

12. In a printing-machine, the combination 125 with a form-carrying cylinder, of a member intermittently rotated from the form-carrying cylinder and when not so rotated is at rest, means for maintaining the member in a position of rest, an impression-cylinder, connections between said member and the impression-cylinder, and means for interrupting 130 said connections at will, substantially as described.

13. In a printing-machine, the combination with a constantly-rotating form-cylinder, of

an impression-cylinder, means whereby the impression-cylinder is given a graduated rotary motion from the form-cylinder and brought to a position of rest once during each revolution, a trip mechanism for interrupting the driving connection between the two cylinders, and means for locking the trip mechanism against operation except when the impression-cylinder is in a position of rest, substantially as described.

14. In a printing-machine, the combination with a constantly-rotating form-cylinder, of an impression-cylinder, means whereby the impression-cylinder is given a graduated rotary motion from the form-cylinder and brought to a position of rest once during each revolution, a trip mechanism for interrupting the driving connection between the two cylinders, and means connected to one of the cylinders for locking the trip mechanism against operation except when the impression-cylinder is in a position of rest, substantially as described.

15. In a printing-machine, the combination with a constantly-rotating form-cylinder, of an impression-cylinder, a gear, means intermediate the gear and the form-cylinder whereby said cylinder imparts a variable movement to the gear, connections between the gear and the impression-cylinder, a trip for interrupting said connections, and means for preventing the operation of the trip except at specified times, substantially as described.

16. In a printing-machine, the combination with a constantly-rotating form-cylinder, of an impression-cylinder, a member intermediate the two cylinders, devices whereby the member is intermittently rotated by the impression-cylinder and when not so rotated is at rest, means for locking the member in its position of rest, connections intermediate the member and the impression-cylinder, a trip mechanism for interrupting said connections, means for preventing the operation of the trip mechanism except at specified times, and means for locking the impression-cylinder when the trip mechanism has disconnected it from the member, substantially as described.

17. In a printing-machine, the combination with a constantly-rotating form-carrying cylinder, of an impression-cylinder, means for giving a rotary motion to the impression-cylinder and for bringing it to a stop once during each revolution of the form-cylinder, a trip mechanism for interrupting the driving connections of the impression-cylinder, means for preventing the operation of the trip mechanism except at specified times, a locking device for locking the impression-cylinder in its position of rest, and means for simultaneously operating the trip mechanism and the locking device, substantially as described.

18. In a printing-machine, the combination

with a constantly-rotating form-cylinder, of an impression-cylinder, means whereby the impression-cylinder is driven from the form-cylinder and brought to a position of rest once during each revolution, a trip mechanism for interrupting the driving connections between the form and impression cylinders, means for preventing the operation of the trip mechanism except at specified times, a locking mechanism for holding the impression-cylinder in a position of rest when tripped, and means for simultaneously operating the trip and the locking mechanisms, substantially as described.

19. The combination of a plate or form cylinder, an impression-cylinder, a wheel mounted on the shaft of the impression-cylinder but separate therefrom, means for connecting the plate-cylinder with the wheel to give rotary motion thereto during a portion of each revolution of the plate-cylinder, and means for connecting and disconnecting at will the impression-cylinder to and from said wheel, substantially as described.

20. The combination of a plate or form cylinder, an impression-cylinder, means for connecting the two cylinders during a portion of the revolution of the plate-cylinder, means for interrupting the driving connections between the two cylinders at the will of the operator, and a safety device for preventing attempted disconnection when the impression-cylinder is in motion, substantially as described.

21. The combination of a plate or form cylinder, an impression-cylinder, a wheel mounted on the shaft of the impression-cylinder but separate therefrom, means for connecting the plate-cylinder with the wheel to give rotary motion thereto during a portion of each revolution of the plate-cylinder, means for connecting and disconnecting at will the impression-cylinder to and from said wheel, and a safety device for preventing attempted disconnection when the impression-cylinder is in motion, substantially as described.

22. The combination of a plate or form cylinder, an impression-cylinder, segmental gearing, coupling-levers carried on one of the cylinders, said gearing and coupling-levers operating to connect the two cylinders during a portion of the revolution of the plate-cylinder, and means for interrupting the driving connection between the two cylinders at the will of the operator, substantially as described.

In testimony whereof I have hereunto set my hand in the presence of two subscribing witnesses.

THOMAS M. NORTH.
